UNITED STATES PATENT OFFICE.

WILLIAM BANCROFT, OF HOPEDALE, MASSACHUSETTS, ASSIGNOR OF ONE-HALF TO THE HOPEDALE MACHINE COMPANY, OF SAME PLACE.

LIFTING-WIRE FOR STOP-MOTIONS OF WARPING-MACHINES.

SPECIFICATION forming part of Letters Patent No. 368,050, dated August 9, 1887.

Application filed August 31, 1886. Serial No. 212,317. (No model.)

To all whom it may concern:

Be it known that I, WILLIAM BANCROFT, of Hopedale, county of Worcester, and State of Massachusetts, have invented an Improvement 5 in Lifting-Wires for Stop-Motions of Warping-Machines, of which the following description, in connection with the accompanying drawings, is a specification, like letters on the drawings representing like parts.

10 Prior to my invention drop-wires in warping-machines have been suspended by the threads so as to drop bodily, or being pivoted between their ends have one end drop when a thread breaks, a dropped wire forming an impediment to the movement of a vibrator or other moving bar or rod, the arresting of the bar or rod effecting through other mechanism the stopping of the machine. In this my invention the wires, one for each thread, are 15 held down by the thread when unbroken; but upon the breakage of a thread the wire is lifted bodily, and hence each thread is controlled by a lifting-wire rather than by a drop-wire, as heretofore.

20 In some prior inventions, where the drop-wires are made as weighted levers pivoted between their ends, when the thread breaks, the thread-holding end rises, owing to the superior weight of the weighted end, which co-operates 25 with the vibrator. The levers or drop-wires have their loads integral therewith. All these pivoted devices work in the arc of a circle. In my invention the drop-wire, or, as herein designated, the "lifting-wire," is lifted bodily 30 when the thread breaks by lifting devices applied thereto detachably instead of integrally, as heretofore, and rises vertically in a right line, so as to bring its heel into position to arrest the vibrator and display its eye above the 35 threads. These wires may thus be replaced when worn or broken by detaching them from their lifting devices and applying new wires to the old lifting devices, thus obviating the expense of replacing the entire devices, as 40 heretofore necessary.

45 My invention consists, therefore, in a "drop-wire," so called, or, as herein called, a "lifting-wire," having a bodily movement in a vertical right line to bring its heel into position 50 to arrest the vibrator and display its eye above

the threads, combined with a guide box or frame and a detachable lifting device, as I will now proceed to particularly set forth and claim.

Figure 1, in section, shows a sufficient portion of a warping-machine with my improved lifting wires or rods added to enable my invention to be understood; and Figs. 2 and 3, modifications, to be described.

The frame-work A, guide-box B, and rolls C 60 and D are and may be of any usual construction.

The vibrator E, consisting, essentially, of an oscillating shaft, e, having two or more arms, e', carrying a long bar, e², and having an arm, e³, to be connected with some moving part of the machine to actuate the vibrator, is substantially like the vibrator shown in United States Patent No. 266,330, to which reference may be had, the said vibrator being moved in 70 like manner.

My improved lifting wires or rods a a' are arranged to slide vertically in holes or slots made in the guide-box B.

Each lifting-wire has at its upper end a 75 guide-eye, 2, through which is extended one of the threads of the warps being handled, each of the said threads, until broken, acting to keep down a lifting-rod, as shown by the full-line position of the lifting-wire or rod a 80 and the dotted-line position of the wire or rod a'; but as soon as a thread breaks, the lifting-wire or rod held down by it is lifted, as in the full-line position of the wire or rod a' and the dotted-line position of the wire or rod a. Each 85 wire or rod a is provided with a heel, b, and each wire or rod a' with a heel, b', the elevation of any one of the said lifting-wires or rods placing its heel in the range of movement of and so as to be struck by the vibrator, the arrest 90 of the vibrator effecting in usual manner the stopping of the machine.

In Fig. 1 each lifting-wire or rod has connected with it one end of a lifting device, f, shown as a lever pivoted at f', the long arm of 95 the said lever being just enough heavier than the short arm as to overcome the weight of the lifting-wire or rod, so that when a thread holding the lifting-wire or rod down is broken the lifting device lifts or thrusts vertically up- 100

ward the wire or rod the thread of which is broken.

Lifting the wires or rods instead of letting them drop, as heretofore, is a matter of very considerable importance, for thereby the location of the broken thread may be more easily detected and the thread may be more readily and quickly applied, as the eye to receive the thread is elevated above the mass of unbroken threads and kept in plain sight.

As an obvious equivalent the lifting device might be a cord connected with the lifting wire or rod and provided with a weight or equivalent, as in Fig. 2; or a spring might be used, as in Fig. 3, the spring being of such strength and so located as to press upward with but slight force the said wires or rods, so that when not held down by a thread the spring would lift them. I prefer the form of lifting device shown in Fig. 1.

It is to be observed that in all of these various forms of lifting devices the said lifting devices are detachably applied to the lifting wire, in contradistinction to making the lifting devices integral with the wire, as has been

practiced heretofore. By making the lifting wire detachable from its lifting device the said wire may be readily replaced when worn or broken, and the old lifting device used with a new wire.

In the drawings, *r* represents a part of the usual reed.

I claim—

The guide box or frame, combined with a series of lifting wires or rods, each having a vertical bodily movement in a right line in said box or frame, and provided with an eye to receive the thread, and automatically-operating detachable lifting devices, substantially as described, for said wires or rods, acting to normally lift said wires or rods bodily as their threads break or run out, substantially as specified.

In testimony whereof I have signed my name to this specification in the presence of two subscribing witnesses.

WILLIAM BANCROFT.
